UNITED STATES PATENT OFFICE

2,185,523

FIREARM

Frederick J. Routledge, Monroe, Mich.

Application April 12, 1937, Serial No. 136,495

4 Claims. (Cl. 42—76)

This invention relates to training equipment for skill in marksmanship.

This invention has utility when incorporated in courses, firing, targets, and projecting equipment therefor.

Referring to the drawings:

Fig. 1 is a plan view of a firing range hereunder;

Fig. 2 is a detail view of a firearm especially adapted for use in this firing range;

Fig. 3 is a section on the line III—III, Fig. 2, showing details of the control for the shot as adapted in the firearm herein;

Fig. 4 is a pattern of shot spread independently of the control herein;

Fig. 5 is a pattern of shot spread under the control herein; and

Fig. 6 is a detail view of a type of shell as used herein, preferably smaller than .5 in its internal bore or say .22 caliber.

Course 1 may hereunder be indoors, say of 40 foot width and 80 foot length in thereby providing a range or course for miniature trap shooting or skeet game. In such set-up there may be adopted the firing line 2, behind which may stand the player to hold firearm 3. Along this course there is shield 4 protecting one on the side thereof remote from the firing line 2 from the shot, where there may be placing of targets 5 in seats 6 of projector 7, adapted to fire or throw in a region between lines of direction 8 and 9 into field 10, herein shown as carrying therebelow a net 11 to entrain or save any targets 5 which may not be destroyed by the marksman.

In this apparatus, the firearm 3 is shown having stock 12, guard 13 for trigger 14, loading and ejecting devices 15 for barrel 16 having internal diameter 17 in which snugly fits shell 18. Beyond this section 16 there is barrel section 19 approximately twice the internal diameter of the barrel section 17. The length of the shell 18 is approximately one inch and that of the bore 17 approximately 12 inches. The bore length of the section 19 is approximately 18 inches. The section 19 locates sight 20. Accordingly, this is a shotgun which, if of smooth bore throughout of dimension 17, would at a position say 10 yards from the firing line 2 show pattern 21 for shot spread. However, with the control section 19 of this firearm the shot of the charge of this shell 18, which normally may comprise DuPont oval powder and charge of 120 #12 shot, will show pattern 22. This controls the spread to such extent that the targets 5 in this range 10 as impinged by the shot are shattered. For such a

set-up the target 5, has dimensions of approximately 2 $\frac{1}{4}$ inch diameter and $\frac{5}{8}$ inch depth, with degree of frangibility to respond to this shot just before the spent throw of such shot.

The projector 7 is herein mounted on a side of the shield 4 away from the firing line 2. A marksman may pull line 32 to set the projector in position for throwing. It is now in order, as the target 5 has been placed, to pull the line 39. This may be effected from the firing line 2 and effect throwing of the target 5 in a controllable range toward the net 11 as well as upward in this range of say twenty-five yards from the firing line 2. In practice, this shield 4 may be about 5 yards from the firing line. The projected targets which are impinged are shattered, but targets which are not struck may be received in the net 11 and reclaimed for subsequent projection. These targets, due to the short range, which in practice may be indoors, adopt a departure from the normal clay pigeon in the slight specific gravity and degree of response to the fracture or shattering.

The disclosure herein is adaptable to a small gage shotgun. However, the achievement herein which is of importance in that on a moving target or with a moving target the marksman has, under the type of firearm herein disclosed, a feel or balance for effective range operation. The experience herein as to the control is favorably comparable with a smooth bore, common diameter shell type of gun wherein the shell diameter is that throughout the barrel. With such a gun having a charge of 120 shot, 25 per cent are within a 6 inch range at 33 feet. With the firearm as herein adopted with the scatter control of the larger diameter barrel section, this has meant with the same type of cartridge, shot and powder at a 33 foot range, 85 per cent of the hits being within the 6 inch circle. This means that, with the type of target as herein disclosed, there is sufficient effectiveness for shattering targets.

Targets sufficiently fragile for use with this apparatus are made with as low an amount of filler as 10 per cent, and such range has been increased without serious detraction up to 20 or 30 per cent in those instances wherein the binder is a petroleum pitch of 175° to 275°. This filler may be clay or ash or other fine powder and operate satisfactorily in the range for the shattering in the marksmanship operations hereunder.

In this range with this control for the scatter, of course, the skill of the marksman is necessarily greater in the pick up, say within 20 to 25 feet of the gun, assuming the shield and projector are say 12 and 15 feet in advance. The effectiveness

of the charge upon a target may extend into 55 to 65 yards before too far spent to effect shattering hereunder.

What is claimed and it is desired to secure by Letters Patent is:

- 5 1. A gun adapted for miniature skeet including a barrel consisting of a smooth bore section of approximately .22 inches bore and another section of at least 25% increase in bore throughout its length, the proportionate lengths of said sections being in the ratio of 2 to 3 respectively.
- 10 2. A gun adapted for miniature skeet shooting including a barrel bored to accommodate a shot cartridge, said bore being approximately .22 inches for a portion of its length adjacent the breech and the remaining portion being bored at least 25% larger, to control the pattern of the shot, the proportionate lengths of said portions being in the ratio of approximately 2 to 3 respectively.
- 15 3. A gun adapted for miniature skeet shooting

including a barrel bored to accommodate a shot cartridge, said bore being approximately .22 inches for a portion of its length adjacent the breech as the minor bore section thereof, and the remaining portion being as much as twice the diameter of the minor bore section throughout its length, to control the pattern for reduced scatter of the shot, the length of the minor bore section being approximately in the range of one-quarter to one-half the length of the barrel.

10 4. A small bore gun adapted for miniature skeet shooting including a barrel bored to accommodate a shot cartridge, said barrel being of a small bore for a portion of its length adjacent the breech and the remaining portion being at least 25% larger, to control the pattern for reduced scatter of the shot, the length of the minor bore section being approximately in the range of one-quarter to one-half the length of the barrel.

20 FREDERICK J. ROUTLEDGE.
